UNITED STATES PATENT OFFICE

171,207

HAND WHEEL FOR CHUCKING TOOLS

Carl H. Ingwer, Elyria, Ohio, assignor to The
Ridge Tool Company, Elyria, Ohio

Application July 8, 1953, Serial No. 25,844

Term of patent 14 years

(Cl. D54—2)

To all whom it may concern:

Be it known that I, Carl H. Ingwer, have invented a new, original, and ornamental Design for a Hand Wheel for Chucking Tools, of which the following is a specification, reference being made to the accompanying drawings forming a part thereof:

Fig. 1 is a top plan view of a hand wheel for chucking tools showing my new design.

Fig. 2 is a bottom plan view; and

Fig. 3 is a sectional view taken along line 3—3 of Fig. 2.

I claim:

The ornamental design for a hand wheel for chucking tools as shown.

CARL H. INGWER.
